UNITED STATES PATENT OFFICE.

EDWARD JOHN RIDGWAY, OF STATEN ISLAND, NEW YORK.

DESIGN FOR A PLATE OR SIMILAR ARTICLE.

Application filed May 4, 1923. Serial No. 6,060. Term of patent 7 years.

To all whom it may concern:

Be it known that I, EDWARD JOHN RIDGWAY, a subject of the King of Great Britain and Ireland, residing at Staten Island, in the county of Richmond, State of New York, have invented a new, original, and ornamental Design for a Plate or Similar Article, of which the following is a specification, reference being had to the accompanying drawings, forming part thereof.

Figure 1 is a face view of a plate showing my new design applied thereto, it being understood that the design is repeated around the entire circumference of the article.

Figure 2 is a side elevation of a plate, with a broken section, showing my new design applied thereto.

Figure 3 is a segment of a plate, drawn to a larger scale, showing my new design in greater detail.

I claim:

The ornamental design for a plate or similar article as shown and described.

In testimony whereof I have signed my name to this specification.

EDWARD JOHN RIDGWAY.
